UNITED STATES PATENT OFFICE.

AUGUST BOUCHERY, OF NEW YORK, N. Y., ASSIGNOR, BY MESNE ASSIGNMENTS, TO THE WALLACE NOVELTY COMPANY, OF NEW YORK, N. Y., A CORPORATION OF NEW YORK.

PORTABLE ELECTRIC-LAMP STAND.

1,132,532.

Specification of Letters Patent. Patented Mar. 16, 1915.

Application filed August 22, 1914. Serial No. 858,009.

To all whom it may concern:

Be it known that I, AUGUST BOUCHERY, a citizen of the United States, residing in the borough of Brooklyn, in the county of 5 Kings, city and State of New York, have invented new and useful Improvements in Portable Electric-Lamp Stands, of which the following is a specification.

This invention relates to portable electric 10 lamp stands, and it is the primary object of the present invention to provide a lamp stand of this character in which the parts may be readily and quickly disassembled and packed into a small, neat and compact 15 structure to take up a minimum amount of space, the supporting base and the shade being adapted to be releasably connected to form a receptacle in which to inclose the lamp socket, a connecting plug and a length 20 of electric current conductor to the ends of which the lamp socket and plug are connected when the lamp stand is not in use and is to be stowed away.

Further objects of the invention relate to 25 a spring clamping member normally concealed by the base but adapted to be pulled out from the base to coöperate with the latter to clamp and support the stand from a suitable support, such as a bed-stead, a 30 dresser, a chair, desk or other object, and to slidably mount a lamp supporting stem in the base and connect it to the clamping member, said stem having a suction supporting device connected thereto to support 35 the stand from a flat surface at an angle to the horizontal, said clamping member coöperating with the suction supporting device and the base whereby the latter will serve as a backing to steady the lamp stand 40 and increase the holding qualities of the suction device when the stand is supported by the latter.

A further object of the invention relates 45 to means to releasably connect the lamp socket to the lamp supporting stem so that the lamp or bulb will extend coaxial with the stem or at an angle thereto.

Another object of the invention is to provide a lamp stand of this character in which 50 the means to connect the lamp socket to the lamp base is adapted to engage in a wooden or like supporting surface, such as the frame of a window or door.

In the drawings accompanying and forming 55 a part of this specification, Figure 1 is

a side elevation of my improved portable electric lamp, the supporting base being partly broken away to illustrate the clamping member and suction supporting device. Fig. 2 is a side elevation of my improved 60 lamp showing the same supported by its clamping arrangement. Fig. 3 is a side elevation of the lamp with the base partly broken away and showing the lamp supported by the suction means from a surface 65 at an angle to the horizontal. Fig. 4 is a side elevation showing the lamp socket supported by the means to connect it to the base. Fig. 5 is a side elevation showing the lamp 70 socket supported by the base to extend laterally therefrom; and Fig. 6 is a sectional side elevation showing the base and shade connected with the socket, plug, current conductor, and the lamp stand and shade supporting means inclosed and concealed by the 75 base and the shade.

Similar characters of reference designate like parts throughout the different views of the drawings.

As stated the object of my invention is to 80 provide a portable electric lamp consisting of two parts, the shade and the base arranged to be releasably connected to provide a receptacle in which are inclosed the lamp stand supporting and shade supporting means, and to also inclose a lamp socket, 85 plug and a length of current conductor, and in the embodiment of my invention illustrated in the drawings I have shown the same as consisting of a base B substantially 90 of bell-shape with the bottom flaring out, and a shade S substantially of dome-shape having means, such as a pair of resilient or yielding loops 7, to support the shade from a globe or bulb at opposite sides to have 95 adjustment about the longitudinal axis of the lamp and also to any angle on an axis transverse to the bulb. The shade is constructed of a suitable resilient or yielding material and the periphery of the bottom is 100 of slightly greater diameter than the bottom of the base to permit it to engage over the bottom of the base, and the bottom of the shade is so constructed that portions thereof will yieldingly engage with the base. As 105 the shade and base are being connected the material of the shade will give or spring and when connected releasably hold them together.

A stem 8 is slidably mounted in the top of 110

the base and a transverse member 11 providing a long bearing for the stem and preventing canting thereof, and to which stem a lamp socket 9 is adapted to be removably connected. To support the lamp stand from a support, such as a bedstead, dresser, chair or the like, I provide a clamping member to coöperate with the base as a clamp. This member consists of a coiled spring 10 inclosed and concealed by the base and preferably wound to conform to the base. The inner coil or whirl of the spring is connected to the stem 8 within the base and the outer coil or whirl engages in a bead at the bottom 15 of the base, as shown at 12, Figs. 1 and 6. The spring at a point between the ends is fixed to the base as by soldering, as shown at 13, Figs. 1 and 6. By this construction a whirl or whirls of the spring adjacent the 20 lower end may be pulled out from the base to engage a support and coöperate with the base as a clamp to firmly secure the lamp to such support as shown in Fig. 2. The coils of the spring adjacent the member end and 25 secured to the stem 8 tend to maintain the stem in its uppermost position but permit said stem to be pushed into the base for a purpose to be hereinafter described.

The stem 8 at its end within the base and 30 within the spring has a suction supporting device, such as a suction cup of rubber 14, to support the lamp from a surface which is at an angle to the horizontal, as shown in Fig. 3. To cause the suction cup to engage with 35 the supporting surface the stem 8 is pushed inward against the tension of the upper coils of the spring forcibly pressing the suction cup against the surface. As the pressure is released on the stem the spring will exert an 40 outward pressure on the stem and constantly exert a pull on the suction cup. This pull on the cup facilitates the holding of the lamp by the cup as it constantly tends to create a vacuum in the cup. Furthermore, the ten- 45 sion of the spring presses the bottom of the base firmly against the supporting surface, whereby the base serves as a backing to prevent sagging and wobbling of the lamp. An essential feature is the construction of the 50 suction cup itself and as shown consists in making the inner top surface relatively flat and to extend substantially the full diameter of the interior of the cup, as shown at 15, with the inner surface merging into the outer 55 surface by a portion 16 inclining inward and downward from the outer to the inner surface, whereby the contacting surface is comparatively thin and very elastic relative to the side walls of the cup and will readily 60 conform and adhere to the surface with which it comes in contact.

As stated the lamp socket is removably connected to the stem 8, and is adapted to be connected thereto to extend coaxial with 65 the stem or laterally therefrom. For this

purpose the socket has a pin 17 to engage in openings 18 extending axially into the end of the stem, or at an angle or transversely through the stem. When the pin is inserted into the opening in the end of the 70 stem the bulb will extend coaxially with the stem, as shown in Figs. 1, 2 and 3, and when the socket is connected to the end of the stem in this manner a tubular portion 19 on the socket embraces the end of the stem. 75 In Fig. 5 the pin 17 engages in a transverse opening in the stem and the lamp and socket are supported by the stand to extend laterally therefrom. By the provision of the pin 17 the lamp may be supported from a 80 wooden window casing, door or the like by forcing the pin thereinto, as clearly shown in Fig. 4. The socket is connected to one end of current conductors 20, the other end of which is connected to a plug 21 to connect 85 the lamp to the source of current at some distance away from the place where the lamp is to be used. The conductor, socket and plug are adapted to be placed into the shade and be inclosed thereby when it is 90 connected to the base, as shown in Fig. 6.

From the foregoing description it will be obvious that I have produced a portable electric lamp which can be disassembled and packed into a compact structure to take up 95 a minimum amount of space, for instance as shown by the dotted lines 22 in Fig. 6, in a traveling bag or case. The specific features of supporting or sustaining the lamp from a suitable support by means of the 100 clamping member and the suction device has been divided out from the present application and constitutes the subject-matter of my copending application, filed January 11, 1915, Serial No. 1558. 105

Variations may be resorted to within the scope of my invention.

Having thus described my invention, I claim:

1. In a portable electric lamp stand the combination of a hollow base having means interior thereof to secure it to a support, with a shade having means to support it upon a bulb, the bottom of the base and shade being provided with means to detachably engage each other to form a closed receptacle in which the base securing and shade supporting means are concealed. 110

2. In a portable lamp stand, the combination of a base having a lamp supporting stem, openings extending axially into and transversely through the stem, with a lamp socket having a pin to engage in the openings in the stem to releasably connect the 115 socket to the stem. 120

3. In a portable electric lamp, the combination of a pair of shells, one of said shells being of a form to constitute the supporting base for the lamp and the other shell of a form to constitute the shade for the lamp, 125 130

the said shells being provided with means to detachably engage each other to form a closed receptacle.

4. In a portable electric lamp, the combination of a pair of sections provided with means whereby they may be connected to form a closed receptacle, one section having means to support it upon an electric lamp bulb to constitute the shade, and the other section having means to connect an electric lamp thereto to constitute the lamp supporting base, substantially as and for the purpose specified.

5. In a portable electric lamp, the combination of a lamp supporting base and a lamp shade, the bottom of said shade being con-

stituted to engage over the bottom of the base and provided with means to detachably engage with the base to form a closed receptacle, substantially as and for the purpose 20 specified.

6. In a portable electric lamp, the combination of a lamp supporting base and a lamp shade, the bottom of said base and shade being constituted to be detachably 25 connected to form a closed receptacle, substantially as and for the purpose specified.

AUGUST BOUCHERY.
